UNITED STATES PATENT OFFICE.

DAVID C. MONTGOMERY, OF ST. JOSEPH, MISSOURI.

REIN-HOLDER.

SPECIFICATION forming part of Letters Patent No. 276,062, dated April 17, 1883.

Application filed January 4, 1883. (No model.)

To all whom it may concern:

Be it known that I, D. C. MONTGOMERY, a citizen of the United States, residing at St. Joseph, in the county of Buchanan and State 5 of Missouri, have invented certain new and useful Improvements in Rein-Holders; and I do declare the following to be a full, clear, and exact description of the invention, such as will enable others skilled in the art to which it app- 10 pertains to make and use the same, reference being had to the accompanying drawings, and to letters or figures of reference marked thereon, which form a part of this specification.

Figure 1 of the drawings is a representation 15 of a face view of my device. Fig. 2 is a rear view of the same, and Fig. 3 is vertical sectional view.

This invention has relation to rein-holders; and it consists in the construction and novel 20 arrangement of parts, hereinafter fully described, and particularly pointed out in the claim appended.

In the accompanying drawings, the letter A designates the dash-board of a buggy or wagon, 25 to which the base-plate B of the rein-holder is designed to be attached by means of screws passing through perforations in the marginal portion of said plate, as indicated at c. At each side of the base-plate B is formed a bearing-lug, d, through which passes the end of a transverse pivot-bar, e, which also passes 30 through lugs g of the lever-plate H and serves to connect the latter to the base-plate. At the upper end of the base-plate are formed lateral 35 guide-lugs L, which extend upward, and are designed to receive between them the reins, when the latter are passed over the upper end of the base-plate.

N represents a lateral bent arm, which is 40 formed on the lower portion of the base-plate, and extends laterally and parallel to the plane of said plate, as indicated at m. The lever-plate H is broad, and extends from the upper edge, p, of the base-plate, over which the reins 45 are passed, to the bent arm N, at the lower

portion of the base-plate. The inner surface of the portion m of the arm N is corrugated, and the lower end of the lever-plate is also corrugated or roughened, as indicated at s, so that when the reins are passed downward between 50 said lever-plate and the arm N they will be clamped between these two portions of the rein-holder. Around the pivot-bar e, which connects the lever-plate to the base-plate, is arranged a spiral spring, z, the extended ends 55 of which respectively engage the base-plate and lever-plate in such a manner as to press the lower portion of the lever-plate against the arm N with some force. When the lower portion of the lever-plate is moved away from the 60 arm N to receive the reins the upper portion of said plate is moved away from the upper edge, p, of the base-plate. Therefore when the reins are in the rein-holder the upper end of the lever-plate is always separated from the 65 edge p, so that when the reins are pulled or jerked by the movements of the horse the forcible bearing of said reins against the upper end of the lever-plate will cause the lower end of said plate to compress them forcibly against 70 the corrugated arm N.

Having described this invention, what I claim, and desire to secure by Letters Patent, is—

A rein-holder consisting of a base-plate, B, 75 having guide-lugs L at its upper end and a lateral bent arm, N, near its lower end, the lever-plate H, pivoted to the base-plate, and extending from the lugs of the latter to its bent arm N, and upward from said lugs L to the 80 upper edge, p, of the base-plate, and the spring z around the pivot-bar of the lever-plate, substantially as specified.

In testimony whereof I affix my signature in presence of two witnesses.

DAVID C. MONTGOMERY.
